GAS STOVE BURNER

George Petersen, Davenport, Iowa, and Harry Petersen, Chicago, Ill.

Application May 14, 1938, Serial No. 207,914

3 Claims. (Cl. 158—117)

The present invention relates to gas burners of the type which is used in kitchen stoves and particularly of the type of gas burners which cannot be extinguished by liquids being spilled on them.

Gas burners which cannot be extinguished by spilled liquids have heretofore been proposed. However, in general, such burners have always been impractical since they are complicated, making them relatively costly and unreliable in operation.

It is accordingly an object of the present invention to provide gas burners which cannot be extinguished by spilled liquids and which, due to their great simplicity, are thoroughly reliable in operation and extremely inexpensive to manufacture. It is a further object to provide burners of this type which are flexible in operation, it being possible to adjust any burner for operation with gases of various thermal capacities. A yet further object is to provide gas burners which it is virtually impossible to blow out when the gas is turned on and lighted.

Other objects and advantages of the present invention will be apparent as the description proceeds.

In accordance with this invention, a feed pipe is provided with an upwardly directed burner end. Below the top of this end a plate is secured which cooperates with a downwardly directed flange on a cap which is screw-threadedly attached to this end of the feed pipe above the plate and defines, with the plate, a gas outlet opening. The cap extends laterally beyond the downwardly directed flange in order to protect the opening from spilled liquids.

For a more complete understanding of this invention, reference may be had to the following description taken in conjunction with the accompanying drawing in which

Fig. 1 is a side elevation of a gas burner in accordance with this invention.

Fig. 2 is a longitudinal vertical section therethrough, and

Fig. 3 is a detail section through the edge of the burner cap.

In the burner shown, a gas feed pipe 1 is connected to the gas supply pipe 2 by a valve 3 of conventional structure. The burner end 4 of the feed pipe is upwardly directed. In the construction shown, the feed pipe and its upwardly directed end are unitary, though within the broad scope of this invention this feed pipe may be an assembly of conventional fittings. The end 4 is screw-threaded as at 5 and is provided with a

circular plate 6, in threaded union therewith, though the plate 6 may be, if desired, secured in any other manner, as by brazing or the like, or it may be made unitary therewith. The plate 6 is provided with an upwardly extending flange 7 about its periphery with the upper surface thereof inclined downwardly and inwardly.

A cap 8 is screw-threadedly attached to the feed pipe above the plate 6 and is provided with a dome 9 which extends laterally, beyond a downwardly extending flange 10, the lower edge of which is complementary to flange 7. An attachment member 11 is secured within the flange 10 and is provided with a screw-threaded opening 12 to fit the screw-threaded portion 5. Gas passages 15 are provided through the member 11 to allow passage of the gas from the feed pipe to an opening 14 between the complementary flanges 7 and 10. The laterally extending edge of the cap is provided with a flange 15 extending downwardly so that any liquids or the like which are spilled on the dome of the burner will drip from this flange and will not run toward the center and down flange 10, stopping the opening 14.

In operation, when the gas is turned on, it will flow through the feed pipe 1 and the end 4. The gas will then flow into the cap 8 and through openings 12 into a chamber 16 between cap 8 and plate 6 and thence out the opening 14 around the burner, when it is lighted. Any liquid or other material similar thereto will, if spilled on the dome 9, drop from the flange 15 free of the opening 14. This opening 14 may then be adjusted for the particular grade of gas being fed, whether natural gas or carbureted water gas. In case of a breeze from any direction, the gas will, when lighted, continue to burn on the lee side of the burner, regardless of the breeze.

As it is obvious many changes may be made in the specific embodiment shown without departing from the scope of this invention, we do not desire to be limited thereto except as so limited by the appended claims.

Having now described our invention, we claim:

1. A gas burner comprising a feed pipe, the burner end of which is upwardly directed, a plate secured to said upwardly directed end, and a cap member vertically adjustable on said upwardly directed end, said cap having a downwardly directed flange to cooperate with said plate in defining a gas outlet opening therebetween, vertical adjustment of said cap member varying the size of said opening, said cap member extending laterally beyond said flange to direct liquids spilled on said burner away from said opening, said cap

extending continuously and imperviously about the end of said feed pipe from the edges of the flange defining said opening.

- 5 2. A gas burner comprising a feed pipe, the burner end of which is upwardly directed, a plate secured to said upwardly directed end, an upwardly directed circular flange on said plate spaced outwardly from said end, and a cap member in screw-threaded union with said upwardly 10 directed end, said cap member having a downwardly directed circular flange to cooperate with the flange on the plate in defining a gas outlet opening between said flanges, and said cap member extending laterally beyond said downwardly 15 directed flange to direct liquids spilled on said burner away from the gas outlet opening, said cap extending continuously and imperviously about the end of said feed pipe from the edges of the flange defining said opening.
- 20 3. A gas burner comprising a feed pipe, the burner end of which is upwardly directed and

externally screw-threaded, a centrally apertured plate having its aperture screw-threaded, said plate having its screw threads engaging the threads of the upwardly directed end of the pipe and having its peripheral portion extending upwardly in a flange, the plate and its flange being spaced downwardly from the end of the pipe, and a cap member vertically adjustable on said upwardly directed end, said cap member having a downwardly directed circular flange to cooperate with the flange on the plate in defining a gas outlet opening between said flanges, and said cap member extending laterally beyond said downwardly directed flange to direct liquids spilled on said burner away from the gas outlet opening, 15 said cap extending continuously and imperviously about the end of said feed pipe from the edges of the flange defining said opening.
